(57) **CLAIM**

The ornamental design for a gas valve assembly with integrated pressure regulator, as shown and described.

DESCRIPTION

FIG. 1 is a perspective view of the gas valve assembly with integrated pressure regulator;

FIG. 2 is another perspective view thereof;

FIG. 3 is another perspective view thereof;

FIG. 4 is front view thereof;

FIG. 5 is a top view thereof;

FIG. 6 is a back view thereof;

FIG. 7 is a bottom view thereof;

FIG. 8 is a side view thereof; and,

FIG. 9 is another side view thereof, showing the side opposite that of FIG. 8.

The broken lines in the drawings are included for the purpose of illustrating portions of the gas valve assembly with integrated pressure regulator and form no part of the claimed design.
